FOREIGN PATENT DOCUMENTS

JP D1383272 * 3/2010

Primary Examiner — Bridget L Eland(74) *Attorney, Agent, or Firm* — Rothwell, Figg, Ernst & Manbeck, P.C.(57) **CLAIM**

The ornamental design for an HVAC control module, as shown and described.

DESCRIPTION

FIG. 1 is a front perspective view of the HVAC control module;

FIG. 2 is a front view of the HVAC control module;

FIG. 3 is a rear view of the HVAC control module;

FIG. 4 is a right side view of the HVAC control module;

FIG. 5 is a left side view of the HVAC control module;

FIG. 6 is a top view of the HVAC control module; and,

FIG. 7 is a bottom view of the HVAC control module.

The broken lines in the drawings illustrate portions of the HVAC control module that form no part of the claimed design.

1 Claim, 5 Drawing Sheets(56)
